BALL RETURN MECHANISM FOR BOWLING
PIN SETTING MACHINES

Rupert E. Rundell, Rockville Centre, and Gustaf E. Hagquist, Brooklyn, N. Y., assignors to American Machine and Foundry Company, a corporation of New Jersey

Application October 30, 1942, Serial No. 463,922

37 Claims. (Cl. 273—49)

1

This invention relates to bowling ball return devices and more particularly to bowling ball returns adapted for use with automatic and semi-automatic bowling pin setting machines, and has for its prime object a decrease in the amount of time required for returning a ball to a player in order that a game may be played with as little interruption as possible due to time lost between the throwing of a ball and its return to a player.

The invention aims to improve existing bowling ball returns in that it takes into consideration the fact that when gravity alone is employed in returning balls, the rapidity with which a ball travels from the pit end of an alley where it is placed upon the ball return runway to the player adjacent the head of the alley depends upon the motion imparted to the ball by the pin boy if pins are set by hand, or if a machine is used for setting pins, generally a lag in the return of a ball to the player arises because of the failure to provide positive means for effecting the return of the ball in a minimum amount of time.

This invention relates, therefore, to bowling ball return mechanism, and more especially to returns designed for use with automatic bowling pin setting machines. It is so constituted that it can be used for single alleys or with two or more alleys in any desired combination. For instance, two alleys can be positioned side by side with a common return running between the two alleys or two or more alleys can be located in conventional manner with the ball return running along one of the alleys in which case the ball is delivered to the runway from each of the several machines by means of a connecting runway extending transversely of the several machines and alleys adjacent the pit ends thereof and connecting with the runway extending along the one alley.

The mechanism of the present invention is readily adapted for use with a bowling pin setting machine of the type shown in co-pending Rundell application, Serial No. 260,901, filed March 10, 1939, for Bowling pin setter, now Patent 2,388,707, granted November 13, 1945, and with mechanism such as disclosed in Hagquist patent, No. 2,293,018, granted August 11, 1942, for Pit elevator for bowling pin setting machines, in which transverse ball delivery supports mounted in the bowling pin setting machine and positioned above the pit of an alley receive a ball at any point theralong and deliver it to a runway which parallels the alley. It has been found that this method of returning balls to the

2

runway may slow the play of the game to some extent and for that reason it is an object of our invention to provide positively actuated ball moving means for accelerating the movement of balls along the transverse ball supports in order to expedite the movement of a ball from the machine, and thereby hasten its delivery to the ball return runway.

It is also an object of our invention to provide means for expediting the ejection of a ball from a bowling pin setting machine and also accelerating its movement along the ball return runway to the head of an alley in a minimum amount of time.

15 It is a further object of our invention to provide an improved ball return mechanism for expediting the removal of balls from a bowling pin setting machine by delivering the ball to a point where its forward travel is practically at a standstill, and then applying a positive forward motion to the ball in an entirely different direction to impart thereto accelerated movement for return to an awaiting player.

It is a further object of our invention to provide improved ball handling mechanism operated in conjunction with a bowling pin setting machine which comes into operation after a ball has been delivered to ball supports extending transversely of a bowling pin setting machine and causes the ball to move by motion in addition to that imparted thereto by gravity in order that the ball may be returned to a player with as little delay as possible.

35 It is a further object of our invention to provide means either forming a part of a runway or co-acting therewith for accelerating the movement of a ball placed thereon so that it will be delivered from a position adjacent the pit end of an alley to the head end in a more positive manner, and thereby eliminate delays in the return of a ball to a player, especially in cases where our novel ball return is used with automatic or semi-automatic bowling pin setting machines.

45 It is an additional object of our invention to provide an improved ball handling and return mechanism which finds an especial use in an automatic or semi-automatic bowling pin setting machine wherein balls removed from the pit of a bowling alley are moved with accelerated motion from the machine, delivered to a gravity return runway and when located thereon subjected to positive forceful movement for increasing the speed of travel of balls along the runway in order to expedite the return of such balls to the head of a bowling alley.

Our invention is further characterized by improved mechanism for handling bowling balls, which mechanism is adapted to be coordinated with the operations of automatic or semi-automatic mechanism of a bowling pin setting machine and wherein balls placed on return devices in such machine are removed more rapidly from the machine and returned along the runway to a player in as short a time as possible.

It is a further object of our invention to provide an improved ball return device for use with two or more bowling alleys wherein balls are delivered from two or more automatic or semi-automatic bowling pin setting machines set into operation substantially simultaneously to a ball return runway in proper timed relation without damage to the balls, and wherein such balls are moved with accelerated motion along the runway to the heads of the alleys.

Our invention also consists in the provision of improved bowling ball return mechanism for use with bowling pin setting machines, which machines are provided with transverse ball supports adapted to receive balls removed from the pits of alleys, and means for expediting the movement of balls along the supports to the ball return runway; the ball return runway being provided with driven conveying means for imparting positive forward travel to each ball placed thereon as it issues from a bowling pin setting machine.

Each of the various elements of the combination is in itself capable of change and modification and certain of the devices employed therein may be used independently of others or by themselves, or they may be replaced by other equivalent mechanisms. However, the mechanism in its preferred form includes means for controlling and coordinating the operation of such devices and for purposes of illustration the invention is shown in the drawings as including preferred combinations of elements which have been found in practice to be practical and serviceable.

In the accompanying drawings which form a part of this specification, and wherein the same reference characters designate the same or like elements:

Figure 1 is a partial sectional side elevation of our improved ball return mechanism taken on line 1—1 of Figure 2;

Figure 2 is a partial end elevation of the mechanism shown in Figure 1;

Figure 3 is a partial plan view taken on line 3—3 of Figure 2;

Figure 4 is a partial side view taken on line 4—4 of Figure 3;

Figure 5 shows a side view of a modified form of our invention as seen from line 5—5 of Figure 6;

Figure 6 is an end view of the mechanism shown in Figure 5;

Figure 7 is a plan view of one form of device used in accelerating the removal of balls from two alleys placed side by side;

Figure 8 is a view taken on line 8—8 of Figure 7;

Figure 9 is a view taken on line 9—9 of Figure 7; and

Figure 10 is a view showing diagrammatically and schematically certain driving connections for operating the mechanism shown in Figures 5 and 6.

In the drawings Figures 1, 2, 3 and 4 disclose a preferred form of our invention in which for purposes of illustration the bowling ball return

mechanism is adapted for use with a bowling pin setting machine of the type shown in Rundell Patent 2,388,707, above referred to. 1, 2, 3 and 4 designate uprights forming a part of the pin setting mechanism, which in the case illustrated consists of two machines mounted on two alleys arranged side by side with a conventional ball return runway of the gravity type located between the two alleys, and serving as a common means for the return of balls to the playing position adjacent the heads of the alleys. Cross member 5 connects the uprights 1, 2, 3 and 4 and longitudinal members 7 form a part of the framework of the machine. As indicated partly diagrammatically in Figure 3 the bowling pin setting machines are mounted above the pits P of the alleys A, and are so arranged that balls can be lifted by suitable means L (Figure 5) which may be of the type shown in Hagquist Patent No. 2,293,018, granted August 11, 1942. Balls from the alley pits are placed on inclined gravity return guide rails 6, 8 so that balls gravitate from one side of each machine towards the other (Figure 3) and roll onto the common return runway designated 10 between the two machines. In the form illustrated, guide rails 6, 8 are mounted above the pit of the bowling alley in the same manner as disclosed in the above referred to Hagquist patent.

In the form of our invention illustrated in Figures 1 to 4, inclusive, each set of ball guide rails 6, 8 has associated therewith an elongated rotating spiral conveyor 12 or 14 adapted to engage a ball as soon as it arrives on the transverse guide rails 6, 8 and impart thereto movement in addition to that caused by gravity so that each ball will move with greater rapidity out of the machine regardless of where it is initially deposited on rails 6, 8, and be delivered as soon as possible onto the return runway mechanism 10 for return to the heads of the alleys. Conveyor 12 or 14 may be made as a single member or a plurality of aligned sections and is provided with spiral threads which engage the ball and propel it along guides 6, 8. As shown, one spiral conveyor is provided for each machine (Figure 3). Spiral conveyor 12 has right-hand threads whereas spiral conveyor 14 has left-hand threads. This difference in structure is necessary in order that balls in both machines will be moved properly towards the center of the two alleys for delivery onto the return conveyor 10. Spiral conveyors 12 and 14 are secured to a shaft 16 by means of set screws 18 and preferably are driven continuously by means of mechanism described hereinafter. The spiral conveyors 12, 14 may be driven singly by suitable driving means (not shown), or by a common means as shown in Figures 2 and 3. The drive is effected by means of a sprocket 20 secured to shaft 16 which is suitably mounted in bearing brackets 21 and 23 connected to uprights 1, 4 and plate 5. A sprocket chain 22 runs on sprocket 20 and sprocket 24. The latter is attached by set screw 26 to one end of the shaft 28. The ends of shaft 28 are mounted in bearing brackets 30 secured to uprights 1 and 2. At one end shaft 28 is provided with a sprocket 32 tracked by a sprocket chain 34 running on a sprocket 36 fast to a shaft 38 journalled in a box bracket 40 secured by screws 42 to a bracket 44 fastened by screws 45 to upright 2 (Figures 1 and 2). Shaft 38 also carries a bevel gear 46 meshing with a bevel gear 48 fixed to shaft 50 also journalled in box bracket 40, which shaft is provided with a

pulley 52 driven by a belt 54 from a suitable motor (not shown). Pulley 52 preferably is continuously driven in order that spiral conveyors 12, 14 may at all times be operating and ready to remove or assist in the removal of balls from the bowling pin setting machines of which they form a part to the return runway mechanism 10, although if desired the pulley 52 may be operated intermittently by suitable mechanism (not shown).

Also fastened to shaft 50 is a pulley 56 which is tracked by a belt 58 driving a pulley 60 loosely mounted on shaft 62. Pulley 60 is provided with a pin 64 to which is attached one end of a coil spring 66 encircling the hub of a collar member 68 secured to shaft 62 and to which collar member the other end of spring 66 is fastened at 69. While it is possible to drive shaft 62 directly from pulley 56, we prefer to use the spring mechanism described hereinabove in order to obtain a quick acceleration of a ball as it arrives on the runway for delivery therealong.

The ball conveyor mechanism in addition to the conventional downwardly inclined gravity section 71 also consists of two parallel elongated rotating spiral members 70, 72 located adjacent the discharge openings in the bowling pin setting machines (not shown). These members are positioned so as to receive each ball as it is ejected from the machine by means of rails 6, 8 alone or by means of rails 6, 8 and transverse spiral member 12 or 14, and then propel such ball with positive force onto the runway section 71. The members 70, 72 can be made from a plurality of aligned sections or a single elongated section (Figure 3). Spiral conveying members 70, 72 are fastened to shafts 62 and 63, respectively, which shafts are journaled in bearing brackets 73, 74. Driving of shaft 63 is effected from shaft 62 by means of a sprocket 61 fastened to shaft 62 and a sprocket 65 secured to shaft 63, both of which are tracked by a chain 67.

By means of the mechanism just described, whenever a ball ejected from a bowling pin setting machine lands upon spiral conveyor members 70, 72, its forward travel is practically zero, and the latter, which are rotating continuously, will cause the ball to be raised and lowered by imparting thereto a "hopping" effect until the ball is properly positioned between the spirals which are designed to fit the curve of the ball. The weight of the ball is such that in the meantime the motion of the spirals has decreased to a point such that coil spring 66 is wound up upon the hub of collar member 68, and finally when a ball is properly positioned between the spirals of conveyor members 70, 72, the stored up tension in the spring becomes greater than the inertia of the ball. Spiral conveyor members 70, 72 are then rotated by the unwinding of the spring at a greater rate than normal. The ball, therefore, has imparted to it a positive driving force by the now rapidly rotating spirals which propel the ball forwardly therealong onto the guide rail portion 71 of the runway mechanism 10 for accelerated movement back to the playing position of the alley. Hence, the movement of the ball is caused by gravity due to the downwardly inclined portion 71 of the return runway, and the positive drive set up by the operation of the spiral conveyor members 70, 72 so that the ball is returned with great rapidity to the playing end of the alley. Any suitable ball braking mechanism, such for instance as that shown in Patent No. 2,236,560 to Bancroft may be em-

ployed for stopping the movement of the ball at the head of an alley.

In Figures 5 and 6 which show a modified form of our invention, uprights 2, 3 and 4 are connected by means of cross channel 76, and longitudinal members 78 fixed to uprights 2, 3 at one end and supported by vertical channel members 80 at their other end form a part of the return runway, designated generally 10. As in the case 10 of the mechanism described hereinabove, balls are lifted from the pit P of a bowling alley A by means of apron L fixed to roller R and slide member S, all constructed and operated in a manner similar to that described in the Hagquist 15 patent, above referred to. Balls are lifted from the pit of an alley at proper times and delivered to rails 6, 8 for delivery from a bowling pin setting machine onto the ball return conveyor mechanism 10. The mechanism shown in Figures 5 and 6 is designed primarily for use with 20 machines mounted on two side by side alleys having a common ball return therebetween, and for that reason transverse ball supports 6, 8 in each machine are usually inclined downwardly 25 towards the space between the two machines (Figure 6) in order to direct balls onto the return runway mechanism 10. In this way one ball after the other, whether they be from the one or both machines, will be placed upon the return runway mechanism 10 and delivered to 30 the head ends of the alleys.

Since it is desirable that the time taken for returning a ball be a minimum in order that play may be continued smoothly or without delay, means has been provided for accelerating the removal or otherwise assisting in the ejection of balls from a machine to the return mechanism 10. For that reason each machine is provided with an auxiliary ball forwarding member designated generally 82. This mechanism consists of a plate 84 having a face inclined downwardly in the direction of travel of a ball out of the machine. Plate 84 preferably is mounted closely adjacent the ball support rail 6 and provided 45 with an inclination greater than that of the ball support rail 6. Plate mechanism 82 also assists materially in breaking up jams of pins if any should tend to lodge between rails 6, 8 and obstruct the passage of a ball therealong. This 50 is due to the upward movement of plate 84 past rail 6 so that stuck pins are shifted and can fall freely between rails 6, 8 into a pin receiving chamber (not shown) not forming a part of this invention.

55 Plate 84 is supported resiliently at two points on levers 86 provided with arms 88 mounting pins 90 about which are positioned springs 92 also encircling pins 94 carried by plate 84 in order to hold the springs in proper relationship 60 with the underside of the plate 84 resting upon the springs. Plate 84 is fixed for relative motion with respect to levers 86 by means of shoulder screws 96 passing through elongated slots formed in the plate and threaded into levers 86. Through 65 this connection plate 84 can have relative motion with respect to levers 86, and thereby exert a yielding upward pressure upon a ball positioned on rails 6, 8 so that as levers 86 are rocked on fulcrum shaft 87, by means of cams 98 engaging cam followers 100 secured to levers 86 each ball is lifted from rail 6 and ejected more rapidly from the machine because of the greater incline of the active face of plate 84. Shaft 87 which 70 mounts levers 86 is suitably secured in uprights 75 3, 4 and provided with collars 89 which maintain

levers 86 positioned in proper working relation with respect to cams 98 mounted on shaft 101 journalled in bearings 103 fixed to the same uprights. A reference to Figure 10 shows that shaft 101 is driven in timed relation with the movement 5 of apron L which removes balls from the pit P of the alley A and delivers them to the guide rails 6, 8 so that after a ball has been positioned on these rails the high portions of cams 98 come into operation to move plate 84 to its operative position with respect to rail 6. In order to assure the proper timed operation of the apron L and the ascending and descending rail plate 84, the bottom of the pit P is provided with a hinged 10 supporting plate 244 (Figure 5) equipped with a spring 246 employed for the purpose of normally separating two contact points 248 and 250, the former of which is attached to plate 244 while the latter is secured to the floor of the pit. The hook-up is such that when a ball lands in the pit, the weight of said ball causes a lowering of 15 the supporting plate 244 and thereby effects a contact of points 248 and 250 and closing of a circuit which energizes solenoid 252 operating a one-revolution clutch 254, of any conventional type such as a Bliss one-revolution clutch attached to sprocket 256 which by means of chain 258 and sprocket 260 is driven continuously by 20 the main shaft 236. By energizing clutch 254 shaft 101 is set into rotation and the operation of the rail plate 84 is effected in proper timed relation with the other operating parts of the pin setting machine with which this mechanism is associated.

The yieldingly mounted ejecting plates 84 may be used alone or in conjunction with other positively actuated ball handling mechanism. As shown in Figures 5 and 6, an auxiliary ball ejecting or rolling unit, designated generally 102, is positioned above the rails 6, 8. Frame members 104, 106 secured to uprights 3, 4, in any suitable manner, support spaced plates 108 in which are journalled shafts 110, 112 mounting pulleys 114, 116, respectively. These pulleys preferably are tracked by a V belt 118 arranged to engage the top of a ball placed on the rails 6, 8, so that as plate 84 is moved by means of cams 98 to lift a ball on rail 6, the top of the ball is brought into frictional driving relationship with the belt 118 and the ball set into positive rolling motion in addition to the motion imparted by gravity thereto whereby it is moved rapidly out of the machine and onto the return conveyor mechanism 10. Shaft 112, which mounts the driven pulley 116 is provided with a sprocket 120 driven by means of a sprocket chain 122 tracking a sprocket 220 mounted on a shaft 222 (Figure 10) which is driven by a bevel gear 224 meshing with a bevel gear 226 secured to a shaft 228. The latter carries a sprocket 230 driven by means of a chain 232 from a sprocket 234 mounted on the main drive shaft 236 of the pin setter machine. Shaft 236 is constantly rotated by a sprocket 238 driven by means of a chain 240 and a sprocket 242 from a motor M. The ball rolling unit 102 is the same for each machine and, therefore, it has been thought necessary to describe but one.

If desired, rail 6 need not be inclined, in which case all gravity rolling motion imparted to a ball initially positioned thereon would be caused by the plate 84 as it is raised by means of cams 98. When a ball rolls out of the machine from a position, such as I to position II (as shown in Figure 6), its movement may stop momentarily after which it travels in a direction substantially

at right angles to its path of movement out of the pin setting machine. In order to continue the rapid return of balls we have provided means for positively moving each ball along the return runway. In the embodiment shown in Figures 5 and 6, a ball lands on spaced endless conveyors 124 traveling on pulleys 126 and 127 mounted on shafts 128, 129 journalled in bearings 130 suitably mounted on longitudinal frame members 78, one end of which is fixed to uprights 2, 3 and the other ends of these members are fixed to vertical supports 80 (Figure 5). Supports 136 connected to longitudinal members 78 carry guide members 138 which extend along the belts adjacent their upper runs and maintain them in proper position with respect to the pulleys and the balls being traveled thereover. Shaft 128 which mounts pulleys 126 is driven by means of a sprocket 140 and sprocket chain 142 from a sprocket 144 mounted on the constantly rotating drive shaft 236 mentioned heretofore (Figure 10).

Each ball arriving on belts 124 is moved forward and delivered to an inclined runway portion 71 forming a part of a conventional type of ball return runway. From this it follows that each ball delivered from the belts 124 onto the inclined portion 71 will have a positive forward motion, which when added to the gravity motion imparted thereto as it rolls down the inclined portion 71 greatly increases its speed and insures its delivery to the playing position of the alley in a minimum of time. In order to impart a more rapid travel to each ball, an auxiliary conveyor, designated generally 154, may be used in conjunction with belts 124 (Figures 5 and 6). This consists of a belt 156 traveling on driving pulley 158 fixed to shaft 160 and a driven pulley 162 mounted on shaft 164.

Shafts 160 and 164 are suitably supported in longitudinal support member 166 pivoted at one end to a pin 167 on a vertical support 168 attached to longitudinal frame member 170. The other end of support 166 is provided with a vertical rod 172 having one end projecting through an opening in an angle member 174 fixed to a part 176 of the machine frame. A spring 178 encircling rod 172 allows yielding movement of the member 166 upwardly and maintains the belt 156 in yielding frictional engagement with the ball as it is being moved by belts 124 and 156 onto the inclined portion 71 of the runway. Nuts 180 on rod 172 support the free end of the rod and allow any adjustments necessary. An adjusting screw 182 having one end mounted in support 50 member 166 and the other end projecting through a hole 184 in shaft 164 is provided with a nut 186 which allows the belt 156 to be tensioned by adjustment of pulley 162 relative to pulley 158. Bracket 188 and gear box 190 provide bearings for a shaft 192 which mounts a helical gear (not shown) meshing with a gear fixed to shaft 160. Shaft 192 has secured thereto a collar 194 mounting on one face thereof a pin 196 to which is attached one end of a coil spring 198 encircling shaft 192 (Figure 5). The other end of the spring is secured to a pin 200 fixed to the face of the sprocket 202 loosely mounted on shaft 192. Sprocket 202 is driven by means of a sprocket chain 204 tracking a sprocket 205 fast to shaft 112 which, as stated hereinabove, is driven by a sprocket 120 and sprocket chain 122. If desired, the normal speed of belts 156 and 124 may be the same. In general, however, it is preferred to drive belt 156 faster than belts 124 75 in order to effect a more rapid delivery of the ball

to the playing end of the alley. Also because of the relationship between collar 194, sprocket 202 and spring 198 encircling shaft 192 whenever a ball moves from position II to a point where it comes under the influence of belt 156, spring 198 will be coiled or tensioned about shaft 192 and at that point where the spring tension overcomes the inertia of the ball, the spring will unwind and impart to the belt 156 a quick propelling action which tends to move the ball forward with greater rapidity onto the inclined portion 71 and thereby lessen the time for its return to the playing position. As shown in Figures 5 and 6, the ball return unit 10 comprising belts 124 and 156 functions to return balls ejected from two bowling pin setting machines and during the operation of these machines, either singly or jointly balls will arrive on the conveyor belts 124 first from one machine and then from the other. If desired, the positions of the cams on shafts 101 of both machines can be so adjusted that one can operate in advance of the other so that in the case where both machines are operating as the result of the substantially simultaneous actuation of the machines due to the rolling of balls down each alley into each pit, the possibility of two balls arriving on the conveyor 124 simultaneously because of the accelerating action of plates 84 is substantially eliminated and danger of denting or chipping balls is practically obviated.

The mechanism shown in Figures 7, 8 and 9 embraces the same operative principle as that shown in Figures 5 and 6 insofar as it pertains to means for expediting the removal of balls from bowling pin setting machines and delivering them to the return runway system 210. As shown for purposes of illustration in Figures 7, 8 and 9, however, two machines are adapted to be placed side by side on the alleys which are provided with a common ball return runway 210 extending along the outer edge of one of the two alleys being served. According to this arrangement of bowling pin setting machines adjacent the pit ends of alleys A1, A2 (Figure 7), it may be advisable in the interest of conserving valuable space and adapting existing alleys for installation of bowling pin setting machines to make it possible for a ball from one machine to pass through the other machine as it travels towards the return runway 210.

That is, as shown in Figure 8, the ball indicated in dotted lines at position I will roll along transverse supporting rails 206b, 208 of one machine and rails 206a and 208 of the other machine onto return conveyor 210. As in the modification shown in Figures 5 and 6, shafts 87 act as fulcrums for levers 86 operated by means of cams (not shown) to raise and lower plates 84a and 84b to lift the balls from their respective rails 206a and 206b in order to subject the ball being removed from the machine to the drive of conveyor 212 which is positioned above rails 206a, 206b and 208 and thereby accelerate the ejection of balls from one or both machines onto conveyor 210. The mechanism in Figures 7, 8 and 9 for mounting and driving belt 212 is to all intents and purposes the same as that illustrated in Figures 5 and 6 described hereinabove and hence further description thereof is deemed unnecessary.

As shown, plates 84a and 84b are overlapped at one end and so arranged with respect to one another that when the machine of which plate 84a forms a part is inoperative, balls will be returned from the other machine when plate 84b

moves into operation and lifts a ball from guide rails 206b and 208. The ball is then rolled by gravity and belt 212 along the upper edge of plate 84b down the inclined portion 214 at the end of plate 84b and along rail 206a and out of the machine onto the return runway 210. If both machines are operating simultaneously, balls will be returned from alley A2 by moving directly from the raised plate 84b onto the raised plate 84a and out on the return runway 210. If the plate 84a should move down before the ball from alley A2 has been delivered to runway 210, the ball will then be returned by rail 206a for the remaining portion of its way across alley A1.

15 The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a bowling ball return device for use with bowling alleys, a ball return runway having an elevated ball receiving portion, means on said runway for receiving a ball at one end of an alley and returning said ball to a player at the other end thereof, a conveyor extending along said portion and located at the receiving end of said runway and coacting with said first-named means for imparting positive motion to said ball to move said ball along said runway, mechanism for driving said conveyor, including means for increasing the rate of travel thereof operable as a result 35 of a ball moving thereon, and mechanism for automatically forwarding and guiding a ball to be returned into the range of operation of said ball receiving means and conveyor.

2. In a bowling pin setting machine having spaced ball supports mounted on said machine and extending generally transversely across said machine and above the pit of an alley adapted to support balls delivered from the pit of a bowling alley, and a gravity ball return for returning balls to the head of said alley constructed and arranged to receive balls from said supports; means for accelerating the delivery of balls along said supports to said return, and means associated with said return to accelerate the movement of a ball in addition to its gravity influenced motion and thereby expedite the return of said ball to said head of said alley, said last-named means including a conveyor extending along said return and cooperating therewith; and mechanism for driving said conveyor including means for accelerating the movement of said conveyor when a ball has been deposited thereon to accelerate the movement of said ball along said return.

3. In a bowling ball return device for use with bowling alleys, a ball return runway comprising ball supporting and delivering guides constructed and arranged to extend along a bowling alley from a ball receiving position adjacent the pit end of an alley to the ball return position adjacent the head end of said alley, said guides being provided with a gravity incline portion near said pit end and an upwardly inclined portion near said head end of said alley, positively actuated conveying means located proximate said ball receiving position for delivery down said gravity incline portion for imparting positive accelerated motion to said ball prior to its movement onto said gravity incline portion of said guides, whereby to accelerate the delivery of a ball to said ball return position, and mechanism for driving

said conveying means including, means for accelerating the movement of said conveying means operative in response to the arrival of a ball thereon.

4. A device for returning bowling balls to the head end of a bowling alley comprising a ball return runway having spaced guide rails extending from a position near the pit end of an alley to the head end thereof, spaced conveyors forming an extension of said ball return runway, means for mounting said conveyors to receive balls from said pit and deliver the same to said rails, and means for driving said conveyors to accelerate the movement of said balls onto said rails for movement along said ball return runway.

5. A device for accelerating the return of bowling balls to a player comprising a ball return runway extending along a bowling alley, said ball return runway including spaced guide rails for receiving a ball at the pit end of said alley and delivering the same to a player at the head end of said alley, an endless conveyor located between said rails at said receiving position, an endless conveyor positioned above said first named conveyor and rails, and means for driving said conveyors to accelerate the movement of a ball along said ball return runway.

6. A device for returning bowling balls to the head end of a bowling alley comprising a ball return runway extending along said alley from a position near the pit end of said alley to said head end, conveying means forming an extension of said ball return runway, means mounting said conveying means for receiving balls and delivering the same to said ball return runway, other conveying means located above said first-named conveying means, and means for driving said conveying means to effect the movement of balls onto said ball return runway.

7. In a bowling ball return for use with a bowling alley, a gravity ball return runway extending along said alley, said runway including ball guides, and a continuously operated conveyor, said conveyor including spring operated means for propelling a ball received on said conveyor with accelerated movement along said guides.

8. In a bowling ball return for use with a bowling alley, a ball return runway, guides on said runway constructed and arranged to receive a ball at the pit end of an alley and deliver the same to the head end thereof, conveyors positioned near the pit end of said runway, means for driving aid conveyors, said means including means for normally driving said conveyors at one rate of speed prior to the positioning of a ball thereon, and mechanism for driving said conveyors at a greatly increased rate of speed subsequent to the arrival of a ball on said conveyors to propel a ball along said runway.

9. In a bowling ball return for use with a bowling alley, a ball return runway, guides on said runway constructed and arranged to receive a ball at the pit end of an alley and deliver the same to the head end thereof, conveyors positioned near the pit end of said runway, means for driving said conveyors, said means including means for driving said conveyors at one rate of speed prior to the positioning of a ball thereon, and mechanism for driving said conveyors at a greatly increased rate of speed subsequent to the arrival of a ball on said conveyors to propel a ball along said runway, said mechanism including a drive shaft, a spring accelerating unit associated with said shaft, and connections between said shaft and unit for storing spring tension in said

unit to effect the desired speed change of said conveyors.

10. In a bowling ball return for use with bowling alleys, a ball return runway extending along an alley, ball guide means on said ball return runway for receiving a ball near the pit end of said alley and delivering the same to a player at the head of said alley, spaced elongated spiral conveyors forming a part of said ball return runway, means mounting said conveyors at the ball receiving position for receiving a ball, and means for driving said spiral conveyors to advance a ball positioned thereon along said ball return runway.

11. In a bowling pin setting machine having inclined gravity ball removing members extending transversely of said machine above the pit of a bowling alley, a ball return positioned to receive balls from said members and return the same to a player at the head of said alley, and means for conveying balls from said pit and delivering the same to said members, an inclined plane movable relative to one of said members, and means for lifting said plane after a ball has been positioned on said members to increase the gravity incline down which said ball travels and thereby accelerate the removal of said ball from said machine to said return.

12. In a bowling pin setting machine having inclined gravity ball removing members extending transversely of said machine above the pit of a bowling alley, a ball return positioned to receive balls from said members and return the same to a player at the head of said alley, and means for conveying balls from said pit and delivering the same to said members, an inclined plane movable relative to one of said members, means for lifting said plane after a ball has been positioned on said members to increase the gravity incline down which said ball travels and thereby accelerate the removal of said ball from said machine to said return, and means coacting with said return for accelerating the movement of said ball therealong to the player.

13. In a bowling pin setting machine having spaced ball supporting members extending transversely across said machine above the pit of a bowling alley, a ball return for returning balls to the head end of said alley, and means for removing balls from said pit and disposing the same on said members, a plate provided with a face inclined downwardly relative to said return, and means operative after a ball has been positioned on said members for moving said plate to engage said ball and form an incline down which said ball travels to said return.

14. In a bowling pin setting machine of the type having ball supports extending transversely across said machine above the pit of an alley, said supports being constructed and arranged to support bowling balls delivered thereto, and a ball return for returning balls to the player; a ball forwarding device comprising a spiral conveying member positioned above said supports and constructed and arranged to engage balls positioned on said supports, and means for driving said member to displace said balls along said supports and expedite the ejection thereof from said machine.

15. In a bowling pin setting machine installation having a plurality of pin setting machines located side by side upon adjacent alleys, a transverse ball guideway mounted in said machines above the pits of said alleys, and means for placing balls removed from said pits upon said guideway.

way for delivering from said machines; mechanism for accelerating the travel of balls along said guideway, said mechanism comprising movable ball engaging members coacting with said guideway, means for mounting one of said members in each of said machines, and means operative whenever a ball has been placed on said guideway in either or both of said machines for moving a member into engagement with said ball.

16. In a bowling pin setting machine installation having a common ball return guideway, a plurality of bowling pin setting machines located side by side adjacent the pit ends of a plurality of bowling alleys, a transverse ball guideway mounted in said machines and common thereto for delivering balls from said machines to said return guideway, and means for placing balls removed from said pits upon said transverse guideway; mechanism for accelerating the movement of balls along said transverse guideway, said mechanism comprising auxiliary ball forwarding devices cooperating with said transverse guideway, and means for moving said devices into engagement with balls deposited on said transverse guideway in timed relation during the operation of said machines to expedite the movement of balls along said transverse guideway and onto said return guideway.

17. In a bowling pin setting machine for use with a bowling alley having a pit at the end of said alley and a bumper in said pit, ball supports extending transversely across said machine, means mounting said supports above said bumper, a ball return for returning balls to the player, and means for delivering balls from said pit and placing the same on said supports for movement therealong out of said machine; a ball forwarding device comprising an endless conveying member positioned above said supports and constructed and arranged to engage balls positioned on said supports, and means for driving said member to travel with and displace said ball along said supports and expedite the ejection thereof from said machine.

18. In a bowling pin setting machine having ball supports extending transversely across said machine above the pit of an alley, said supports being constructed and arranged to support bowling balls delivered thereto, and a ball return for delivering balls to the head of said alley, means for accelerating the ejection of a ball from said machine onto said return, said means including a belt conveyor having a ball engaging lap extending along and coacting with said supports to accelerate the travel of a ball along said supports and out of said machine, and mechanism for accelerating the movement of each ball upon ejection from said machine onto said return along said return and back to the head of said alley.

19. In a bowling pin setting machine installation having a plurality of pin setting machines located side by side upon adjacent alleys, a common transverse ball guideway mounted in said machines above the pits of said alleys, and means for placing balls removed from said pits upon said guideway for delivery from said machines; mechanism for accelerating the travel of balls along said guideway, said mechanism comprising movable ball engaging members coacting with said guideway, means for mounting one of said members in each of said machines, means operative whenever a ball has been placed on said guideway in either or both of said machines for moving a member into engagement with said ball, and a common ball return runway positioned to receive

balls discharged from said guideway for returning said balls to the head ends of said alleys.

20. In a bowling pin setting machine installation having a common ball return guideway, a plurality of bowling pin setting machines located side by side adjacent the pit ends of a plurality of bowling alleys, a transverse ball guideway mounted in said machines and common thereto for delivering balls from said machines to said return guideway, and means for placing balls removed from said pits upon said transverse guideway; mechanism for accelerating the movement of balls along said guideway, said mechanism comprising inclined plane accelerating members, means mounting one of said members in each of said machines, means for moving said members independently and relative to said guideway, and timed mechanism operative to cause the movement of said members into engagement with balls on said guideway to accelerate the movement thereof through said machines and onto said return guideway.

21. In a bowling pin setting machine for use with a bowling alley having a pit at one end thereof, and a bumper mounted in said pit, inclined gravity ball supporting and ejecting guides extending transversely across said machine, means mounting said guides above said bumper, a ball return located exteriorly of said machine and positioned to receive a ball delivered thereto by said guides for return to a player, an auxiliary ball forwarding device mounted for cooperation with said guides, said device being constructed and arranged to engage a ball moving along said guides and means for moving said device relative to said guides and a ball located thereon to accelerate the ejection of said ball from said machine and delivery onto said return.

22. In a bowling pin setting machine for use with a bowling alley having a pit at the end of said alley and a bumper mounted in said pit, a ball supporting and delivering guideway extending transversely of said machine for supporting and guiding a ball out of said machine, a ball forwarding device positioned above said guideway and constructed and arranged to engage balls located thereon; and means for driving said device to displace a ball along said guideway and expedite the ejection thereof from said machine.

23. In a bowling pin setting machine, a transverse ball supporting and delivery guideway, means mounting said guideway in said machine above the pit of a bowling alley, a ball return for returning a ball ejected from said machine to a player, and mechanism coacting with said guideway for accelerating the ejection of a ball from said machine onto said return, said mechanism including a belt conveyor having a ball engaging lap extending substantially parallel with said guideway, and means for driving said conveyor to accelerate the movement of a ball along said guideway, out of said machine and onto said return.

24. In a bowling pin setting machine installation having a plurality of pin setting machines located side by side upon adjacent bowling alleys, ball guideways mounted in said machines and constructed and arranged to support and eject from said machines balls delivered thereto from the pits of said alleys for return to players at the head end of the alleys, a ball return runway parallel to said alleys, and positively actuated ball forwarding mechanism coacting with said guideways for moving balls along said guideways out of said machines and onto said return runway.

25. In a bowling pin setting machine installation, the combination with a plurality of bowling alleys, of a plurality of bowling pin setting machines, one machine positioned at the pin supporting end of each alley, a common ball supporting and ejecting guideway extending transversely of said machines and positioned above said alleys, a ball return runway located adjacent one of said machines and positioned to receive balls ejected from each machine and delivered thereto by said guideway, and positively actuated mechanism coacting with said guideway for moving balls on said guideway onto said runway.

26. In a bowling pin setting machine, guide means for receiving a ball delivered from the pit of a bowling alley and ejecting said ball from said machine, a ball return runway for returning a ball to a player, said runway having a ball receiving portion, means mounting said receiving portion in position to receive a ball ejected from said machine by said guide means, and auxiliary ball ejecting mechanism coacting with said guide means for imparting accelerated motion to a ball to expedite the movement of said ball onto said portion of said runway, said mechanism including an endless belt having a lap extending substantially parallel with said guide means and positioned for frictional engagement with a ball on said guide means, and means for driving said belt.

27. In a bowling alley installation, the combination with a plurality of alleys, of a plurality of pin setting machines positioned at the rear ends of said alleys, a common ball guideway extending transversely of said machines and positioned above each alley, means for controlling the passage of balls onto and along said guideway from one machine and through another, and positively actuated ball conveying mechanism coacting with said guideway for expediting the movement of said balls through and out of said machines.

28. The combination defined in claim 24 wherein said mechanism comprises belt conveyors each having a ball engaging lap extending substantially parallel with said guideways, and means for driving said belts.

29. The combination defined in claim 24 wherein said return runway is mounted between said machines, and said mechanism comprises belt conveyors each having a ball engaging lap extending substantially parallel with said guideways, and means for driving said conveyors in opposite directions to advance balls on said guideways to said return runway.

30. The combination defined in claim 24 wherein said return runway is mounted between said machines, and said mechanism comprises belt conveyors, each of said conveyors having a ball engaging lap extending substantially parallel with said guideways, means for driving said conveyors in opposite directions, and auxiliary conveying means cooperating with said runway for accelerating the movement of balls delivered thereon from said guideways back to the players.

31. The combination defined in claim 25 wherein said mechanism comprises a belt conveyor having a ball engaging lap extending substantially parallel with said guideway, and means for driving said conveyor to move balls out of said machines and onto said return runway.

32. The combination defined in claim 25 wherein said mechanism comprises a belt conveyor having a ball engaging lap coacting with said guideway, and means for driving said conveyor to move balls along said guideway out of said machines and onto said runway, and mechanism for con-

trolling the movement of balls from one machine through another en route to said runway.

33. In a bowling pin setting machine located adjacent the pit end of a bowling alley having a bumper at the rear end of the pit, and a ball return runway, spaced substantially elongated ball receiving and conveying members including an elongated spiral conveyor mounted above said pit and bumper, supports mounting said members substantially transversely of said machine, and means for rotating said spiral conveyor to impart a positive conveying movement to a ball for delivering the same onto said return runway.

34. A bowling ball return mechanism for use with a bowling alley having a pin setting machine located at the pit end thereof comprising transversely extending ball guides for delivering a ball to a point of discharge, means mounting said guides in said machine above said pit, a ball return runway located exteriorly of said machine adjacent said point of discharge of a ball from said guides for receiving a bowling ball from said transverse guides at a position proximate the pit end of said alley and delivering said ball to a player at the head end of said alley, said ball return runway being provided with a downwardly sloping gravity incline near said pit end of said alley, positively actuated movable means having an elongated ball engaging surface positioned to engage a ball on said guides at a point spaced from the guides, and extending lengthwise therewith for engaging and accelerating the movement of said ball along said transverse guides out of said machine and directly onto said ball return runway, and conveying means coacting with said runway for accelerating the initial movement of a ball along said ball return runway and onto said downwardly inclined portion thereof for expediting the delivery of said ball to the player.

35. In a bowling pin setting machine for use with a bowling alley having a pit at one end thereof, and a bumper at the rear of said pit, a transverse ball supporting and delivery guideway for ejecting a ball delivered thereto from said pit to a point of discharge out of said machine for return to the player, means mounting said guideway above said bumper, a ball return positioned adjacent said point of discharge of the ball from said guideway to receive a ball ejected by said guideway from said machine, a movable auxiliary ball ejecting device having an elongated ball engaging portion extending along said guideway and positioned to engage a ball moving along said guideway at a point spaced from said guideway, and means for operating said device to effect movement of said elongated portion relative to said guideway and a ball located thereon to accelerate the movement of said ball along said guideway and the ejection of said ball from said machine onto said return.

36. In a bowling pin setting machine located adjacent the pit end of a bowling alley having a bumper at the rear end of said pit, a laterally inclined ball ejecting guideway, supports mounting said guideway above said bumper and substantially transversely of said machine, said guideway comprising a ball supporting and guiding member, and an elongated positively actuated conveyor spaced from said member and positioned to engage a ball on said guideway at a point spaced from said guideway, a ball return runway positioned to receive a ball directly from said guideway, and means for effecting conveying movement of said conveyor to accelerate the

movement of a ball along said guideway and out of said machine directly onto said runway.

37. In a bowling pin setting machine installation having a plurality of pin setting machines located side by side upon adjacent bowling alleys, each comprising a pit, ball guideways mounted in said machines and constructed and arranged to support and eject from said machines balls delivered thereto from the pits of said alleys for return to players at the head end of the alleys, each machine comprising means for automatically lifting balls from the pit to said guideway, a common ball return runway paralleling said alleys, ball operated means for initiating the operation of each machine, ball engaging means coacting with each of said guideways for positively ejecting balls from said guideways onto said common runway, and means for causing the operation of said ball engaging means successively in predetermined timed relationship when both of said side by side machines are substantially simultaneously set into operation, thereby tending to prevent the simultaneous delivery of balls

from both of said side by side machines onto said common ball return runway.

RUPERT E. RUNDELL.
